ABSTRACT OF THE DISCLOSURE

A 100 kw. average power X-band tube is disclosed which employs a highly convergent linear beam of electrons focused by means of a shielded solenoid. The solenoid has a cathode pole piece which includes a reentrant central portion. The cathode emitter is located in the plane of the mouth of the reentrant portion. Electrons emitted from the cathode are focused into a highly convergent beam, i.e., area convergence greater than thirty, such as 50:1, 70:1 or 100:1 and projected through a narrow throat portion of the reentrant pole piece structure into a uniform region of beam focusing magnetic field.

The solenoid includes a cylindrical magnetic yoke which surrounds the solenoid and serves to produce an axially symmetric convergent magnetic field of the precise and proper convergence between the cathode emitter and the place where the beam reaches its minimum diameter to eliminate or minimize beam scalloping.

In one embodiment, a modulating anode electrode is also disposed within the reentrant cathode pole piece structure. A tubular portion of the modulating anode projects into the narrow throat of the magnetic pole piece and is insulated and spaced from the pole piece which operates at main anode potential.

Description of the prior art

Heretofore, 100 kw. average power X-band klystron tubes have been built which employed a split solenoid with a rectangular open-yoke having a pair of mutually opposed reentrant pole pieces. The magnetic beam focusing structure was similar to that described in U.S. Patent 2,928,972, issued Mar. 15, 1960 and assigned to the same assignee as the present invention. In this prior tube, there were 5 axially spaced stagger tuned cavity resonators in a magnetic gap having a length of about 3.5". The tube had a bandwidth of about 0.5%. It was desired to provide an instantaneous bandwidth of 4%. In order to provide 4% instantaneous bandwidth, the output circuit would require a plurality of coupled cavities thereby extending the length of the magnetic circuit from 3.5" to between 5.5" and 7" depending upon the type of buncher and output circuits used. Such a long magnetic gap of relatively intense field as of 3.5 to 4.5 kg. coupled with the requirement of a highly convergent beam, i.e., area convergence greater than 30 and very low beam interception, i.e., less than 1% and reasonable radio frequency efficiencies of 45% at X-band mitigate against the use of a split-solenoid open-yoke electromagnet. More particularly, the split-solenoid produces a dip in the beam focusing field in the gap of the magnet. This dip tends to cause beam blow-up and to produce amplification of beam scalloping. Also beam scalloping is aggravated by the open-yoke structure since the convergent magnetic field in the electron gun is not always symmetric about the circumference of the beam due to saturation of the pole pieces and the non-symmetric nature of the open-yoke structure.

Cylindrical closed-yoke solenoidal electromagnets have also been used for focusing linear beam tubes. However,

2

in such prior magnetic circuits the cathode is generally axially spaced outside of the pole plate disposed adjacent the cathode (cathode pole plate). A tubular magnetic field shaping member is employed which projects axially from the cathode pole plate toward and around the cathode emitter. The tubular field shaping member serves to shield the cathode from the leakage flux from the magnet. However, such magnetic circuits fail to provide the necessary degree and rate of magnetic field convergence in the electron gun, and do not provide the necessary degree of shielding.

Summary of the present invention

The principal object of the present invention is the provision of an improved beam focusing magnetic circuit for linear beam tubes.

One feature of the present invention is the provision of a beam focusing magnetic circuit for a high convergence linear beam tube including a solenoid surrounded by an enclosing magnetic yoke having a reentrant cathode pole structure at one end and a cathode emitter disposed near the plane of the mouth of the reentrant portion for projecting a beam of electrons through a throat portion of the pole into a uniform beam focus magnetic field, whereby the high convergence beam is focused over a substantial gap length without beam blow-up or scalloping.

Another feature of the present invention is the same as the preceding feature including the provision of a modulating anode electrode disposed within the reentrant portion of the cathode pole piece and having a tubular section extending into the throat of the reentrant pole piece structure in spaced relation therefrom, whereby the beam is modulated as desired.

Another feature of the present invention is the same as any one or more of the preceding features wherein the region of uniform magnetic field in the gap of the electromagnet is constant to within 10% of its peak intensity, whereby beam blow-up and scalloping are minimized.

Other features and advantages of the present invention will become apparent upon a perusal of the following specification taken in connection with the accompanying drawings wherein:

Brief description of the drawings

FIGURE 1 is a longitudinal view, partly in section, of a prior art beam focusing electromagnet,

FIGURE 2 is a view of the structure of FIGURE 1, partly broken away, taken along line 2—2 in direction of the arrows,

FIGURE 3 is a plot of magnetic field intensity versus axial distance along the centerline of the structure of FIGURE 1,

FIGURE 4 is a longitudinal sectional view, partly schematic, of a prior art beam focus solenoid,

FIGURE 5 is a schematic line diagram of a beam profile showing beam scalloping and blow-up,

FIGURE 6 is a longitudinal sectional view of a microwave tube and its beam focusing solenoid incorporating features of the present invention,

FIGURE 7 is a reduced sectional view of the structure of FIGURE 6 taken along line 7—7 in the direction of the arrows,

FIGURE 8 is a schematic diagram of the gun portion of the structure of FIGURE 6 delineated by line 8—8 with a plot of beam profile and magnetic field versus axial and radial distances superimposed thereon, and

FIGURE 9 is an enlarged sectional view of an alternative structure to that portion of the structure of FIGURE 6 delineated by line 8—8.

Description of the preferred embodiments

Referring now to FIGURES 1 and 2 there is shown a prior art open-yoke split-solenoid beam focusing electromagnet as used for narrow band X-band high power klystron tubes. The magnetic circuit includes a rectangular yoke 1, a soft iron, having two coaxially disposed hollow reentrant pole pieces 2 and 3, as of soft iron. A magnetic gap 4 is defined between the opposed inwardly tapered ends of pole pieces 2 and 3. A solenoid which is split into two series connected sections 5 and 6 is wound over the pole pieces 2 and 3.

An X-band 5 cavity klystron amplifier 7, only partially shown, is coaxially disposed of the hollow pole pieces 2 and 3 and of the gap 4. The beam focusing magnet produces a magnetic field on the axis of the beam within the klystron 7 as shown in FIGURE 3. The cathode emitter 8 of the tube 7, schematically shown in FIGURE 1, is disposed in the convergent region of the magnetic field. The magnetic pole structure 2 is shaped such that the magnetic flux lines in the electron gun region are matched to the trajectories that the electrons will follow under electrostatic forces alone. The convergence of the magnetic field in the electron gun region is determined by finding the proper size and position of the hole in the cathode pole piece 2 so that the magnetic flux leaking through it from the main magnet gap 4 will match the desired electron trajectories.

Due to the split nature of the solenoid 5 and 6, the beam focusing field H has a substantial dip in the center of the gap 4. The gap 4 is only about 3.5" long and, thus, the magnetic field dips from a high value to a lower value in a relatively short distance. This abrupt change in the magnetic field tends to cause beam blow-up and to amplify beam scalloping, as indicated by line 11 of FIGURE 5. If the dip in field intensity were not present, the beam would not blow up and would follow the profile trajectory indicated by line 12 of FIGURE 5. Also, the beam scalloping would be damped by the uniform field. The beam scalloping is caused by departure of the magnetic field from the proper shape in the gun region. Scalloping is encountered in the open-yoke design of FIGURES 1 and 2 due to the lack of symmetry of the field about the circumference of the beam due to the lack of symmetry of the open-yoke structure 1 and magnetic saturation effects in the pole structure.

Referring now to FIGURE 4 there is shown another prior art magnetic beam focusing electromagnet 13. In this design, longer magnetic gaps are obtained with more uniform beam focusing magnetic fields, as indicated by the dotted line 14 of FIGURE 3. The electromagnet 13 includes a solenoid 15 surrounded by a cylindrical magnetic yoke 16 which is closed at its ends by a pair of annular pole plates 17 and 18, as of iron. The magnetic field is shaped in the region of the electron gun 8 by means of tubular iron projection 21 which projects from the cathode pole plate 17 toward and around the cathode emitter 8. A non-magnetic anode insert 22 forms the anode electrode. While the magnet 13 provides a uniform field over a relatively long gap it provides insufficient convergence for high convergence electron guns, i.e., area convergence greater than 30 to 1 and preferably in the range of 50:1 to 100:1.

Referring now to FIGURES 6-8, there is shown a linear beam X-band tube incorporating features of the present invention. The magnetic circuit includes a cylindrical solenoid 31 separated into three closely spaced segments separated by water-cooled plates 32, as of copper. The plates 32, as of 0.250" thick, include annular coolant channels 33 connected to a source of liquid coolant via pipes 34.

A cylindrical magnetic yoke 35, as of 0.625" thick soft iron, with an outside diameter of 16" and a length of 8.25" surrounds the solenoid 31 in spaced relation. The solenoid is wound on a cylindrical non-magnetic frame 36, as of 0.125" thick copper with an outside diameter

of 9.250". The yoke 35 includes a pair of end plates 37 and 38, as of 0.750" thick soft iron. The plates 37 and 38 are each formed by a pair of concentric ring portions. The outer ring portions are fixedly secured to the cylindrical yoke portion 35, whereas, the inner ring portions form the pole pieces 37' and 38' of a linear X-band amplifier tube 39.

The amplifier tube 39 includes an evacuated envelope having a main body portion 41 closed at one end by an electron gun assembly 42 and closed at the other end by a beam collector structure 43. The main body portion 41 includes a microwave interaction circuit for interaction with a beam of electrons to produce an amplified output signal. The interaction circuit comprises 6 klystron type driver cavity resonators 44 which are stagger tuned over a band of interest and a three-coupled cavity extended interaction output cavity resonator 45. Signals to be amplified are coupled into the first resonator 44' via a waveguide, not shown. The second resonator 44'' is heavily loaded to an external resistive load via a second waveguide 46. The amplified output signal having an instantaneous bandwidth of 4% at X-band and an average power of 100 kw. is coupled from the output resonator 45 via a third waveguide, not shown. The waveguides are brought out of the tube 39 through three 120° peripherally spaced holes 47 in the collector pole piece 38', see FIGURE 7.

The cathode pole piece 37' includes a reentrant pole structure formed by a counter bore 51 (see FIGURE 8) in the plate 37'. The bore 51 defines a mouth portion 52 of the reentrant pole structure. The bore 51 terminates short of passing through the plate 37'. A second bore 53 which is coaxial of the first bore 51 and of lesser diameter defines a throat portion 54 of the reentrant pole structure. A concave cathode emitter 55 is disposed on the axis of the tube 39 with the emitting surface intersecting the centerline of the tube 39 at a point 56 which is approximately at the entrance plane 57 of the mouth 52. A cylindrical beam focus electrode 58 surrounds the cathode emitter 55 for electrostatically focusing the beam. A modulating anode electrode 59 surrounds the beam path within the mouth 52 of the reentrant pole structure. The modulating anode electrode includes a tubular portion 61, as of copper, which extends into the throat 54 of the reentrant pole piece 37'.

The pole piece 37' is sealed to a portion of the main body 41, as of copper. The main body 41 includes a first axial bore 62 of the same diameter as the throat 54 of the pole 37' and a second bore 63 forming the beam hole of the main anode. The pole piece 37' and main body 41 are operated at main anode potential which is typically ground potential. The cathode 55 and focus electrode 58 are operated negative with respect to the anode as of, for example, -37 kv. The modulating anode 59 is insulated via insulators, not shown, from both the cathode 55 and anode 41 and is pulsed between anode and cathode potential for pulsing the beam current, as of 7.2 amps.

The mouth and throat portions 52 and 54 of the reentrant pole piece 37' are dimensioned relative to the cathode emitter 55 such that all the flux contained within the beam circumference at a point of its minimum diameter within the main body 41 also threads through the cathode emitter surface. This is achieved in the magnetic focusing structure of the present invention by positioning the cathode emitter 55 at the entrance plane 57 of the mouth 52 of the reentrant pole structure 37' and dimensioning and shaping the mouth 52 and throat 54 portions so that the magnetic flux leaking through the throat 54 from the main focusing field will match the convergent electron trajectories in the gun region that the electrons would follow under electrostatic forces alone. The dimensions for such a magnet circuit and electron gun design are shown in FIGURE 8 with both axial and radial scales provide for a 50:1 area convergence, 1.0×10^{-6}

beam permeance, 37 kv.-7.2 amp beam, and employing a main focusing magnetic field H of 3 kg, which is 2.5 times the Brillouin field intensity. The variation of the beam focusing magnetic field on the beam axis is shown by dotted line 71 of FIGURE 8. The magnetic gap between the poles 37' and 38' is approximately 7.75" long.

In general, for magnetic circuits of the present invention, point 56 of the cathode emitter 55 falls within 0.5 times the radius R of the cathode from the entrance plane 57 of the mouth 52 of the reentrant pole structure 37'. Also, the larger bore 51 has a radius falling between 2 and 4 times the radius R of the cathode 55. The length of the mouth 52 falls within 2 and 3 times the radius R of the cathode emitter 55. The throat 54 has a radius falling between 0.75 and 2 times the radius of the cathode and a length less than 1 radius of the cathode. In addition, the magnetic field H_0 in the main field region in the gap between the pole pieces 37' and 38' peaks near the poles and dips to a minimum value which is within 10% of the peak intensity to prevent beam blow up.

In the reentrant pole design of the present invention, a preponderance of the leakage field used for converging the beam in the gun region terminates on the inside wall of the bore 51. In this region and in the annular plate-like region of the pole 37', the soft iron members are relatively thick to prevent magnetic saturation effects. As a consequence, the magnetic field may be varied over a relatively wide range as from 1800 gauss to 4000 gauss as the beam voltage is changed without disturbing the proper shape of the beam focusing field.

Referring now to FIGURE 9, there is shown an alternative electron gun and reentrant pole structure. The apparatus is essentially identical to the structure of FIGURE 8 except that the modulating anode 59 has been eliminated and replaced by the main anode 41 which fills the throat portion 54 of the reentrant pole structure 37'. The gun of FIGURE 9 has a permeance of 1.0×10^{-6} , the main magnetic field H has a value of 4 kg., the beam voltage is 85 kv. with a 1" diameter cathode 55 and a beam area convergence of 40:1. The tube using the gun of FIGURE 9 has an efficiency of 45% at X-band. The beam interception is about 0.05% and the drift tube filling factor is about 70%. The beam power is 2.1 megawatts continuous.

Since many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. In a microwave tube apparatus; means for forming and projecting a beam of electrons over an elongated beam path; means at the terminal end of the beam path for collecting and dissipating the energy of the electrons; means forming a microwave circuit disposed along the beam path between said beam-forming means and said beam-collecting means for interaction with the beam to produce an output microwave signal; means forming a magnetic circuit for focusing the beam over its path between said beam-forming means and said beam-collecting means; said magnetic circuit including, a solenoid co-

5 axially disposed of the beam path, a magnetic yoke made of magnetically permeable material surrounding said solenoid and having a pair of centrally apertured pole piece structures through which the beam passes, one of said pole pieces forming the cathode pole piece and being disposed at the upstream end of the beam path, the improvement wherein; said cathode pole piece is reentrant having a mouth portion and a throat portion; said beam forming means including a cathode emitter disposed at the mouth portion of said reentrant pole piece structure for emitting the beam of electrons through said throat portion of said cathode pole piece structure; said mouth and throat portions of said pole piece being shaped so that the beam-focusing magnetic flux lines in said throat and mouth portions and which pass through said cathode emitter are converged to a cross-sectional area near said throat portion which is less than $\frac{1}{30}$ of the cross-sectional area of the beam at said cathode emitter, and wherein said mouth portion of said reentrant cathode pole structure is formed by an axially-directed counter bore in said pole piece, said bore having a radius of between 2 and 4 times the radius of said cathode emitter, and said bore having an axial length on the beam axis of between 2 and 3 times the radius of said cathode emitter.

20 2. The apparatus of claim 1 including a modulating anode electrode structure coaxially disposed of the beam path within said mouth portion of said cathode pole structure, said modulating anode electrode having a tubular extension projecting axially of the beam path into the throat portion of said pole structure.

25 3. The apparatus of claim 1 wherein said throat portion of said reentrant cathode pole structure is defined by a second axial bore in said pole structure of lesser diameter than and coaxial with said first bore, and wherein said second bore has a radius between 0.75 and 2 times the radius of said cathode emitter and a length less than 1 radius of said cathode emitter.

30 4. The apparatus of claim 1 wherein the emitting surface of said cathode emitter intersects the centerline of the beam at a point which is less than one-half of the radius of said cathode emitter from the entrance plane of said mouth portion of said reentrant cathode pole structure.

35 5. The apparatus of claim 1 wherein said magnetic circuit means produces a region of axially-directed beam focusing magnetic field which reaches peak amplitudes near said pair of pole structures and which sags to a minimum amplitude between said peaks, and wherein said minimum amplitude is within 10% of the highest peak amplitude, whereby beam blow up is minimized.
